*Inventor
Frederick S. Otis*

Dec 1578

Frederick S. Ohs, of Brooklyn, N.Y.
Bellows Patent No. 1578, dated May 13, 1869.

The schedule referred to in this Bellows Patent and making part of the same

Dec. 15 78

To all whom it may concern:

Be it known that I, F. J. Otis, of Brooklyn in the County of Kings and State of New York, have produced a new and ornamental Design for a Clock Case Front; and I do hereby declare that the following is a full, clear and exact description of the same, reference being had to the accompanying drawing, forming part of this specification.

The drawing represents a face view of my design.

The leading features of this design are two pairs of columns erected on high square bases which are connected by a semi-circular arch, and an entablature common to both pairs of columns and rising in the centre, as will be hereinafter more fully explained and described.

Two pairs of columns A. A. are set on bases B. B. which are united by a semi-circular arch C. and which are supported by a common bed plate D. This bed plate is square, with a slight projection in the centre, and it is surmounted by mouldings a. b. c. representing oyes and filllets. The chief parts of the bases B. B. are two square blocks d. the faces of which are ornamented by a series of flat, depressed mouldings d' extending from the surfaces of the blocks down to the oblong, four-sided plates or metopes d''.

The upper edges of said blocks are ornamented by astragals d''', from which cavetto e. rise to the plinths f. of the columns A.

The arch C. rests on the astragals d''', and it joins by a series of mouldings g. the door-like metope g. and from this metope, mouldings g'', extend up on the sides of the blocks d.

The plinth f. of each column consists of a torus f', fillet f'', scotia f''' and astragal f''', and each shaft is ornamented by a wreath g. wound spirally round it, as clearly shown in the drawing.

The capital E. of each column consists of a fillet h', ogee h'' and fillet h''', and an abacus h, which joins the abacus

N.Y. 1578

of the adjoining column. The capitals I, support the entablature which is common to both pairs of columns, and which consists of the architrave I, the frieze G, and the cornice H.

The architrave I, is ornamented by a series of mouldings, consisting of two fillets i. i', a cymatium or ogee i², and a band i³.

The frieze G, consists of a square face k, and ogee k', and the cornice H, is composed of five members, the lowest of which is a square band l, followed by an ovolu l', fillet l'', ogee l''', and finally by a square band l⁴.

The central portion of the entablature between the two pairs of columns rises up in two sweeps m, joined by the central arch n. The sweeps m, gradually decrease from the bottom up to the top of the entablature, until on the last band l⁴ of the cornice they are reduced to two small quadrants m', and in the same measure the central arch n, increases as clearly shown in the drawing.

Having thus fully described my design, what I claim as new and desire to secure by Letters Patent, is

The columns A. A, arranged as described; the spiral wreaths g, blocks d, central arch c and entablature I. G. H, all as shown and specified.

Witnesses.
